UNITED STATES PATENT OFFICE.

JAMES CAVANAGH, OF BOSTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SHOE.

1,268,432.

Specification of Letters Patent.

Patented June 4, 1918.

Application filed September 23, 1914. Serial No. 863,122.

To all whom it may concern:

Be it known that I, JAMES CAVANAGH, a citizen of the United States, residing at Boston, in the county of Suffolk and State of Massachusetts, have invented certain Improvements in Shoes, of which the following description, in connection with the accompanying drawings, is a specification, like reference characters on the drawings 10 indicating like parts in the several figures.

This invention relates to boots and shoes and particularly to counters or stiffeners for the heels of shoes.

Counters or heel stiffeners heretofore used 15 in the manufacture of boots and shoes have been molded from leather or leather-board and although they are satisfactory as a shape producing element for the heel end of the shoe and prevent the shoe from being 20 misshaped by the heel of the foot of the wearer they present a hard, non-resilient surface to engage the heel of the foot. This often causes considerable discomfort to the wearer and frequently, too, allows the heel 25 portion of the shoe to slip up and down on the heel, the slipping of the shoe in the heel being particularly objectionable in Oxford or low cut shoes and is due to the fact that the heel end of the shoe does not 30 conform properly to the contour of the heel of the foot of the wearer.

An object of the present invention is to provide an improved counter or heel stiffener which will retain its shape under all 35 conditions of use and wear and at the same time readily conform itself to the conformation of the heel portion of the foot and present a cushion surface to engage the heel.

Other objects and features of the present 40 invention will appear from the following description when considered in connection with the accompanying drawings and will then be pointed out in the claims.

In the drawings;

Fig. 1 is a perspective view, partly in section of a counter embodying the features of the present invention;

Fig. 2 is a sectional view through the heel portion of a shoe embodying the present invention and showing the relative position of the heel of a foot to the counter; and

Fig. 3 is a sectional view similar to Fig. 2 showing the condition of the counter before the foot is inserted.

The counter herein illustrated as showing 55 a preferred embodiment of the present invention comprises a body portion 2 of leather or similar material molded to embrace the heel of the foot and preferably has an inturned flange 3 which overlies the 60 margin of the heel seat of the innersole and is secured thereto. The inner or foot engaging portion of the counter consists of a cushioning material 6 cemented or otherwise secured to the body portion 2 of the 65 molded counter. This cushioning material is preferably sponge rubber or other soft rubber and is of sufficient resiliency and thickness to conform readily to the heel of the foot and to allow the ball of the wearer's 70 foot to embed itself therein. The combined thickness of the body portion 2 and the sponge rubber 6 is such that the stiffener decreases in thickness toward the upper edge of the counter so as to facilitate the 75 entrance of the foot of the wearer into the shoe. When incorporated in a shoe the counter is inserted between the upper 8 and lining 9 and the shoe is then preferably lasted in the usual manner. In lasting the 80 shoe the upper materials are preferably drawn snugly around the heel of the last and the cushion 6 is thereby placed under compression and more or less condensed so that when the shoe is completed and the last 85 removed from the machine the cushion 6 resumes its normal condition as shown in Fig. 3. Thus the foot receiving space normally provided in the shoe is reduced, this reduction in the interior dimensions of the 90 shoe increasing gradually from the ankle portion of the shoe to the ball of the shoe. When the foot is inserted in the shoe the cushion counter 6 will be compressed to the conformation of the heel of the foot and 95 will snugly hug the wearer's foot, the ball A of the heel being embedded into the cushion as shown in Fig. 2 and the cushion fitting the neck B of the heel instead of standing away from the neck as does a 100 counter of usual construction. Under this arrangement the shoe is prevented from slipping up and down on the heel, which is particularly objectionable in Oxford and low cut types of shoes, and the uncomfortable chafing and resultant wear on the stocking and lining is avoided. Moreover, the 105 rubber cushion 6 besides presenting a soft

resilient surface to engage the heel acts as a protecting member to prevent moisture from the foot reaching and deteriorating the counter.

5 Having described my invention, what I claim as new and desire to secure by Letters Patent of the United States is:

1. A heel stiffener for boots and shoes comprising a stiffening member formed to prevent an upright heel shape retaining element in a shoe and an inwardly bent flange for attachment to the shoe innersole, and a cushioning member extending upwardly along the inner face of said element and 10 above the ball of the heel of the wearer's foot and horizontally around the ball and of sufficient depth to allow said ball of the heel to embed itself in the cushioning member while said member closely embraces the 15 relatively small neck portion of the foot 20 immediately above the ball of the heel.

2. A heel stiffener for boots and shoes consisting of a stiff body portion molded to the required shape, and a layer of sponge rubber secured to the inner surface of said stiff body portion, said rubber being of sufficient thickness to allow the ball of the heel of the wearer's foot to embed itself therein.

30 3. A heel stiffener for boots and shoes consisting of a member of relatively stiff material molded to the required shape, and a heel receiving member of a material adapted to be displaced into exact conformation with

the contour of the entire heel portion of the 35 wearer's foot when engaged thereby.

4. In a shoe, the combination with a heel stiffening member, and a cushioning member related thereto to extend around the heel of the wearer, of an upper and a lining 40 between which the stiffening and cushioning members are located with the latter member and the lining projecting inwardly to reduce the normal foot receiving space, whereby the ball of the heel of the wearer 45 embeds itself in said cushioning material during use of the shoe.

5. In a shoe the combination with an innersole, an upper, a heel stiffener and a lining which extends from the top of the shoe downwardly under the innersole, of a cushion located between the lining and the stiffener at the back of the heel and extending from near the innersole upwardly above the ball of the heel of the wearer, said 50 cushion being adapted normally to reduce the heel receiving space required by the heel and to be displaced into conformation with the heel upon the insertion of the foot 55 in the shoe.

In testimony whereof I have signed my name to this specification in the presence of two subscribing witnesses.

JAMES CAVANAGH.

WILLIAM B. KING.

Correction in Letters Patent No. 1,268,432.

It is hereby certified that in Letters Patent No. 1,268,432, granted June 4, 1918, upon the application of James Cavanagh, of Boston, Massachusetts, for an improvement in "Shoes," an error appears in the printed specification requiring correction as follows: Page 2, line 10, claim 1, for the word "prevent" read *present*; and that the said Letters Patent should be read with this correction therein that the same may conform to the record of the case in the Patent Office.

Signed and sealed this 8th day of October, A. D., 1918.

R. F. WHITEHEAD,

Acting Commissioner of Patents.
